U. F. CLEMONS

APPARATUS FOR REFINING HYDROCARBON OILS

Filed June 7, 1923

Fig. 2.

U. F. Clemons
INVENTOR.
BY *John M. Spellman*
ATTORNEYS.

UNITED STATES PATENT OFFICE.

ULYSSES F. CLEMONS, OF MARSHALL, OKLAHOMA.

APPARATUS FOR REFINING HYDROCARBON OILS.

Application filed June 7, 1923. Serial No. 643,913.

To all whom it may concern:

Be it known that I, ULYSSES F. CLEMONS, citizen of the United States, residing at Marshall, in the county of Logan and State 5 of Oklahoma, have invented certain new and useful Improvements in Apparatus for Refining Hydrocarbon Oils, of which the following is a specification.

This invention relates to certain new and 10 useful improvements in apparatus for refining hydrocarbon oils and more particularly is an improvement upon my Letters Patent No. 1449734 dated March 27, 1923.

In my prior patent, the bed of fuller's 15 earth extends throughout the entire area of the tank with the result that the capacity of the still as reduced.

The present invention has for its primary 20 object to provide a still of maximum capacity and accordingly proposes a still with an enlarged dome, both as to diameter and height, which is equipped with a floor supporting a bed of fuller's earth.

A further object of the invention is to provide 25 means for preventing the fuller's earth from dropping down from the dome and into the body of oil contained in the tank.

In the drawings:—

Figure 1, is a side elevation of the invention, parts being broken away and shown 30 in section, and

Figure 2, is a section on line 2—2 of Figure 1.

In proceeding in accordance with the present 35 invention a tank 1 is employed heated by oil burners 2 or other suitable means.

The tank is provided with a dome 3 of suitable diameter and height and which exceeds the usual diameter and height of domes 40 of ordinary construction with which tanks of this type are generally or usually equipped.

A foraminous floor 4 is provided for the dome and upon which is supported a bed of 45 fuller's earth 5.

As illustrated more particularly in Figure 2 of the drawings, the sides 6 of the dome are parallel and extend considerably below the top 7 of the tank, so as to afford a 50 dome not only of increased height, but one

possessed of a diameter nearly approximating the diameter of the tank. It will also be noted that the vapor space 8 below the floor 4 is of the same and full depth as the vapor space existing between the top 7 of 55 the tank and the level of the crude petroleum or hydrocarbon oil 9 contained within the tank. In this manner the entire area of the floor 4, which latter is itself of relative considerable area, is completely exposed to the 60 vapor.

For the purpose of preventing the fuller's earth in the dome from dropping down into the oil in the tank, a pan 13 is provided which is suspended by hangers 14 from the 65 top of the tank so as to afford inlets 15 through which the vapor passes in entering the dome. The pan is of a size greater than the diameter of the dome so as to effectually catch any particles of the fuller's earth 70 which may drop from the dome.

A condenser is connected by a pipe 11 to the top of the dome, the pipe having an automatic check valve therein which opens upon a predetermined pressure of vapor being 75 reached in the tank.

What is claimed is:—

An apparatus for refining crude petroleum and hydrocarbon oils, including an oil tank, heating means for the tank, a dome for the tank of large diameter and height relative to the tank and having opposed sides which extend considerably below the top of the tank, a foraminous floor for the dome arranged so that the space between the floor 80 and the surface of the oil in the tank is of the same depth as the space between the surface of the oil and the top of the tank, a bed of fuller's earth on the floor, an outlet at the top of the dome, a pan in the dome in spaced relation to and beneath the floor so as to catch any particles of the earth dropping from the dome, and means to connect said pan to the tank whereby to afford spaces 85 between the margin of the pan and the top of the tank to permit the vapors to enter the dome. 90

In testimony whereof I affix my signature.

ULYSSES F. CLEMONS.
